UNITED STATES PATENT OFFICE

105,692

DESIGN FOR A BASKET

Robert F. Carpenter, Cleveland, Ohio

Application November 25, 1936, Serial No. 66,126

Term of patent 7 years

To all whom it may concern:

Be it known that I, Robert F. Carpenter, a citizen of the United States, residing at Cleveland, in the county of Cuyahoga and State of Ohio, have invented a new, original, and ornamental Design for a Basket, of which the following is a specification, reference being had to the accompanying drawing, forming part thereof.

Fig. 1 is a perspective view of a basket showing my new design; and

Fig. 2 is an end view thereof.

I claim:

The ornamental design for a basket, as shown.

ROBERT F. CARPENTER.
